UNITED STATES PATENT OFFICE

HELEN THOMAS HUEY, OF STONEHURST, PENNSYLVANIA

DISHWASHING TOOL AND SPRAY

Application filed March 14, 1931. Serial No. 522,692.

The present invention relates to an improved dish washing tool and spray, and a purpose of the invention is to provide a handle for the reception of a spray nozzle at one end and a flexible tube inserted into the opposite end with a connector uniting the spray nozzle and the flexible tube on the interior of the handle, in conjunction with a brush in curved formation in conjunction with the spray nozzle for washing and spraying the dishes, in conjunction with means for attaching the brush to the handle.

Another purpose is to provide a spray nozzle, which divergently enlarges from a tubular portion of the nozzle, with a flattened face arranged adjacent the curved brush and provided with perforations in the flattened face for the purpose of spraying water through the brush on to the dishes, at the same time the brush is used for brushing the dishes in order to remove the soil or dirt thereon.

Still another purpose is a provision of a brush having spring arms which fit in diametrically opposite grooves of the handle, 25 with lugs engaging in depressions at certain ends of the grooves, in conjunction with a sleeve fitting the handle and provided with opposite means to overlie the spring arms to lock them in said grooves.

A further purpose is to provide means for preventing the spray nozzle from turning relative to the handle, in conjunction with diametrically opposite bayonet connections or joints to hold the sleeve in position on the handle.

It is to be understood that the particulars herein given are in no way limitative, and that while still keeping within the scope of the invention, any desired modification of details and proportions may be made in the construction of the appliance according to circumstances.

The invention comprises further features 45 and combination of parts to be hereinafter

set forth, shown in the drawing and claimed.

In the drawing:—

Figure 1 is a view in perspective of the improved dish washing tool and spray constructed in accordance with the invention. 50

Figure 2 is a longitudinal sectional view through the same more clearly showing the connection between the spray nozzle and the flexible tube.

Figure 3 is a cross sectional view on line 55 3—3 of Figure 2 showing how the spring arms of the brush are locked in the groove of the handle and how the spray nozzle is prevented from turning in the handle.

Figure 4 is a detail view of the spray nozzle 60 detached showing the perforated face thereof.

Figure 5 shows a group of views of the connection of the sleeve, the spring arms of the brush, and the grooved end of the handle. 65

Figure 6 is a detail sectional view of one end of the handle showing the grooves 7.

Referring to the drawing 1 identifies a handle which may be any length and any diameter in cross section and any configuration. The handle is hollow, and one end thereof receives the tubular end 2 of the spray nozzle 3. A rib 4 is formed on the tubular end of the spray nozzle and is designed to engage a notch 5. The tubular end 75 of the spray nozzle has an abutment ridge or flange, which abuts the face of a sleeve 6, which telescopically fits over the tapered end of the handle, and hence limiting the insertion of the tubular end of the spray nozzle. 80

Diametrically opposite portions of the tapered end of the handle are provided with diametrically opposite longitudinal grooves 7, in which the spring arms 8 of a loop formed brush 9 engage. Certain ends of the 85 grooves 7 have notches or depressions 10 deeper than the bottoms of the grooves for the reception of the lugs 11 at the ends of the spring arms of the brush.

The sleeve 6 as previously stated tele- 90

scopically fits the tapered end of the handle, and diametrically opposite portions of the wall of the sleeve are provided with longitudinal channels 12 through which the spring 5 arms of the brush pass, when assembling the construction. The end face of the sleeve has slots 13 which adjoin the channels allowing the sleeve to have a partial rotation on the tapered end of the handle, so that the wall 10 of the sleeve may overlie the spring arms of the brush, and retain said spring arms in the grooves of the handle. Diametrically opposite portions of the sleeve at positions at right angles to the channels have bayonet slots 14, 15 which are engaged by the headed pins or lugs 15, for the purpose of locking the sleeve on the tapered end of the handle, especially after the sleeve has been imparted a partial rotation, such as will enable the sleeve to overlie 20 the spring arms and retain them in the grooves and hence prevent the lugs of the spring arms from disengaging the notches or depressions at the ends of the grooves.

A flexible tube or hose 16 engages into the 25 handle at its end opposite the sleeve, and this flexible hose telescopically fits over a tubular connector or union 17 which passes through the handle and telescopically unites with the tubular end of the spray. The other end of 30 the flexible hose has a conventional type of socket connection 18 which connects the hose to a conventional type of spigot. By this arrangement of dish washing tool and spray the socket end of the flexible hose may be attached to a spigot, and in this case the operator may grasp the handle, applying the brush to the dishes, and due to the operative connection with the spigot water will pass through the hose through the connector in the inside of 35 40 the handle and then through the nozzle and hence escape through the perforations in the flat face of the nozzle. The streams of the spray will easily percolate through the circular brush, and due to the brush having radial bristles for passage over the faces of the dishes the soil or dirt thereon may be easily removed, whereas the spray will act to wash 45 the dishes.

The invention having been set forth, what 50 is claimed is:

In a dish washing tool and spray, the combination with a hollow handle, of a tube fitting telescopically through the handle and provided with a bead at one end to enter one 55 end of a rubber supply hose, which also fits partially into the rear end of the handle, the interior of the handle at its other end having a tapered portion constituting a socket and provided with exterior diametrically opposite longitudinal grooves merging into notches at their rear ends, a brush provided 60 with opposite spring arms engaging said grooves and having their terminals fitting the notches, a sleeve fitting the exterior of the 65 forward end of the handle and provided with

bayonet connections with the handle and said sleeve adapted to be partially rotated to override the spring arms of the brush to hold them in the grooves and their terminals in the notches, said sleeve having an end wall 70 adjacent the extremity of the handle, said end wall having a notch, a spray nozzle provided with a broad flat perforated spray face, flatwise toward the brush, said nozzle merging into a tubular shank fitting within the 75 socket of the handle and provided with a longitudinal exterior rib to engage the notch of said end wall of the sleeve, thereby holding the flat face of the nozzle flatwise in register with the brush.

In testimony whereof I affix my signature.

HELEN THOMAS HUEY.
